R-F PHASE SHIFTER

James J. Nail, Basking Ridge, N. J., assignor to International Telephone and Telegraph Corporation, a corporation of Maryland

Application June 25, 1952, Serial No. 295,502

12 Claims. (Cl. 343—100)

This invention relates to R-F. phase shifters and more particularly to high speed R-F. phase shifters of the capacitive type for use at ultra-high frequencies.

It is often desirable to have azimuthal omnidirectional antenna pattern coverage, and yet in many situations this type of coverage cannot be obtained by the installation of a single antenna due to the physical characteristics of the antenna site. In such situations it is possible to obtain omnidirectional coverage by arranging a number of directional antennas each covering a sector of the azimuth. Normal operation of such an antenna system allows the coverage of a particular portion of the azimuth at any instant of time, and if only one sector is of interest, a higher antenna gain is obtainable through the use of the single directional antenna for that sector. However, if continuous omnidirectional coverage is to be obtained from such a directional antenna system, it is possible to connect the individual antennas in parallel, but then interference between the antenna patterns will cause regions to exist having deep minima radiation characteristics. If the phase of the signals fed to interfering antennas is shifted so that the input to one pair of antennas is 180° out of phase with the input to the other pair, it causes the minima and maxima regions of the antenna pattern to be interchanged, resulting in a substantial azimuthal omnidirectional pattern if the phase shift be continuous.

One of the objects of this invention therefore is to provide a high speed R-F. phase shifter for use with a sector antenna system to provide substantial omnidirectional coverage.

Another object of this invention is to provide a high speed R-F. phase shifter whereby the phase shift may be made a desired function of time.

A further object of this invention is to provide a high speed capacitive type R-F. phase shifter which may be utilized with a sector antenna system to provide omnidirectional coverage without causing interference with the received signal.

The above-mentioned and other features and objects of this invention will become more apparent by reference to the following description taken in conjunction with the accompanying drawings, in which:

Fig. 1 is an illustration of the radiation pattern obtained from an omnidirectional antenna system utilizing four directional antennas;

Fig. 2 is a schematic diagram in cross section of one embodiment of this invention;

Fig. 2A is a schematic drawing of the equivalent electrical circuit of the embodiment of this invention shown in Fig. 2;

Fig. 3 is a plan view of the rotating disc utilized with the embodiment of this invention shown in Fig. 2;

Fig. 4 is a view in elevation of the peripheral portion of the rotating disc of Fig. 3;

Figs. 5 and 6 are graphic illustrations helpful in the explanation of this invention.

2

Figs. 7, 8, and 9 are sectional views similar to Fig. 4 showing modified embodiments of the rotating disc of Fig. 3; and

Fig. 10 is a schematic illustration of another embodiment of this invention.

Referring to Fig. 1 of the drawing, an omnidirectional antenna system azimuthal radiation pattern, shown therein by the solid lines, comprises the radiation patterns due to four directional antenna arrays 1, 2, 3, and 4, each covering approximately a 90° azimuth sector. It is seen from the pattern of Fig. 1 that the radiations due to adjacent directional antennas interfere with each other, distorting the normal directional pattern of each antenna and causing regions, such as 5, to exist wherein a plurality of radiation pattern lobes 6 will be present, between which areas of minimum signal intensity, such as 7, are present. A receiver located in an area of minimum signal intensity 7 will not pick up any signals from the antenna system. However, if opposite antennas 1 and 3 and 2 and 4 are tied together and the energy from transmitter 8 is fed directly to one pair of antennas and a 180° phase shift is introduced by a phase shift device 9 before the energy from transmitter 8 is coupled to the other pair of antennas, then the radiation pattern lobes 6 will shift, causing the position of the maxima and minima radiation intensity to be interchanged, as shown by the dotted line radiation pattern of Fig. 1. If the proper phase shift is introduced, a receiver located at point 7 will now pick up the emissions of the antenna system. However, a receiver now located at 10 will not receive any signals, although the receiver at point 7 was able to receive the signals prior to the introduction of the phase shift. If a continuous phase shift is introduced into the radiated signals, the areas of maximum and minimum signal intensity will continuously vary, providing substantial omnidirectional coverage from the directional sector array. However, the frequency of the phase shift must be so selected that interference with the received signals is not presented. In communication systems utilizing audio frequencies, the phase shift must be selected at a frequency outside the audible frequency pass band to prevent interference.

Referring to Fig. 2, a high band R-F. phase shifter shown therein in accordance with the principles of this invention comprises a coaxial transmission line 11 having a slot 12 cut in the circumference of its outer conductor 13. A section of the inner conductor 14 is cut away to form gap 15 in line with slot 12. A form of endless carrier, such as disc 16, consisting of a non-conducting low loss material, such as fiberglass, is caused to revolve with the peripheral edge passing through slot 12 so that a metallic rim 17 or other conductive parts attached to the periphery of the disc 16 passes through gap 15. A coaxial inductive stub 18 is coupled to the coaxial transmission line 11, having its inner conductor 19 coupled to inner conductor 14 and its outer conductor 20 coupled to outer conductor 13.

Referring to Fig. 2A, the equivalent schematic diagram of the structure of Fig. 2 is shown, wherein the capacitive coupling across gap 15 of the inner conductor 14 due to metallic rim 17 is represented as a capacitor 21 and the coaxial stub 18 is shown to be the equivalent of a shunt inductance 22. Thus it is apparent that the high pass filter of Fig. 2A is the equivalent schematic diagram of the structure of Fig. 2.

Referring to Fig. 3, the rotating disc 16 of Fig. 2 is shown comprising a non-conducting low loss material having an attached metallic rim 17. As the metallic rim 17 moves in gap 15, it causes a capacitive coupling to occur between the separated portions of inner conductor 14. The capacitance between the metallic rim 17

and the inner conductor 14 varies in accordance with the width or body configuration of the metallic rim. In one application it is desirable to obtain a phase shift that is a sinusoidal function of time because such a function of time reduces the inherent harmonic losses of on-off type of switching, so the width of metallic rim 17 is made to vary in a sinusoidal manner as it passes through gap 15. Thus, as shown in Fig. 4, the metallic rim 17 is composed of metallic parts or teeth 23; and as a succession of metallic teeth 23 pass through gap 15, the width of metal bridging gap 15 will vary as a sinusoidal function of time, causing a change in capacitance proportional to the change in width of the metallic rim 17 passing through gap 15. Since the input energy to the coaxial transmission line 11 is of constant frequency, a variation in the capacitance of the circuit will cause a proportional shift in the phase of the energy flowing through the transmission line. Since the capacitance changes as a sinusoidal function of time, the phase shift of the energy flowing through coaxial line 11 will vary as a sinusoidal function of time. The size of the disc 16, the speed of rotation, and the distance between minimum and maximum rim thickness are dependent upon the frequency of phase shift that is desired. Thus for a disc 16 having a 12-inch diameter rotated at 5000 R. P. M. with a distance between points of minimum and maximum rim thickness of one-quarter inch produces a phase shift of 6300 C. P. S.

Referring to Fig. 5 a graphic illustration of a series of curves each representing a different capacitance is shown wherein the ordinate shows the phase shift, due to a change in capacitance, for a given frequency which is measured along the abscissa. If at any instance of time the value of capacitance introduced into transmission line 11 by the metallic rims 17 of disc 16 is equal to C_1 , the energy transmitted through line 11 at frequency ω_1 will have a phase angle equal to β_1 , as shown in Fig. 5. If the value of capacitance 21 is changed to C_2 , then the phase of the energy transmitted through line 11 at frequency ω_1 will be equal to β_2 . Thus if the capacitance introduced into gap 15 by rim 17 is varied between C_1 and C_2 , the phase angle of the energy transmitted by line 11 will vary between β_1 and β_2 , or in other words, a phase shift equal to $\beta_2 - \beta_1$ will be introduced into transmission line 11 when the input energy is at frequency ω_1 .

As shown in Fig. 6, for a given input frequency ω_2 there is a critical capacitance C_3 below which any change will cause attenuation of the energy flowing through line 11. If the capacitance introduced into gap 15 is made to vary between C_3 and C_4 , the energy flowing through the transmission line 11 at frequency ω_2 will be alternately transmitted and attenuated.

If rim 17 is composed of alternate teeth, metallic ones 26 and insulating ones 27, as shown in Fig. 7, the capacity introduced into line 11 may be made to vary between points C_3 and C_4 of Fig. 6 alternately attenuating and passing the energy transmitted by line 11. Thus by proper adjustment of the capacitance introduced into line 11, the energy flow through line 11 may be passed or stopped, allowing this invention to be utilized as a high speed capacitive switch.

If a gradual phase shift from zero to some upper limit with an almost instantaneous return to zero is desired, the teeth of the metallic rim 17 may be shaped in a triangular manner, as shown in Fig. 8, causing a "sawtooth" change in phase.

If a phase shift is desired which will vary between two predetermined angles, the teeth of metallic rim 17 may be made alternately wide and thin, as shown in Fig. 9.

When a large phase shift is desired over a relatively large bandwidth, it is necessary to introduce a large change in capacitance. As shown in Fig. 10, this is possible by driving several discs 30, 31, and 32 from the same shaft 33 through a plurality of gaps 34, 35, and 36 in coaxial transmission line 37. Inductance stubs 38, 39,

and 40 are coupled to line 37 between the discs 34, 35, and 36, which may be made very thin and spaced a distance just sufficient to allow a stub to be placed between them.

While I have described above the principles of my invention in connection with specific apparatus, it is to be clearly understood that this description is made only by way of example and not as a limitation to the scope of my invention as set forth in the objects thereof and in the accompanying claims.

I claim:

1. A phase shifter type device comprising a coaxial transmission line having the inner conductor thereof with a gap therein, a coaxial inductive stub disposed adjacent said gap with the outer and inner conductors thereof coupled to the inner and outer conductors, respectively, of said line, the outer conductor of said line having a slot in alignment with said gap, a shaft disposed for rotation about an axis parallel to said coaxial line, means including a body carried on said shaft for movement during a rotation movement of said shaft through said slot and said gap, said body varying in dielectric-affecting material in a direction circumferential along the path of movement of said body to thereby continuously change the total value of the dielectric across said gap, thus giving rise to a continuously varying capacitance.

2. A phase shifter type device according to claim 1, wherein said capacitive body includes an endless element of conductive material of varying width.

3. A phase shifter type device according to claim 2, wherein said element includes a plurality of distinct conductive parts.

4. A phase shifter type device according to claim 3, wherein said parts are in a spaced series relation.

5. A phase shifter type device according to claim 3, wherein the width of each of said parts varies in a sinusoidal manner.

6. A phase shifter type device according to claim 3, wherein said parts are each of a triangular shape in cross section.

7. A phase shifter type device according to claim 3, wherein said parts are of varying width.

8. A phase shifter type device comprising a coaxial transmission line having the inner conductor with a plurality of spaced gaps therein, a plurality of inductive coaxial stubs, one spaced adjacent each of said gaps and having its outer and inner conductors coupled to the outer and inner conductors of said transmission line, the outer conductor of said line having a plurality of slots each respectively in alignment with one of a plurality of said gaps, a shaft disposed for rotation about an axis parallel to the said coaxial line, means including a plurality of bodies respectively carried on said shaft for movement during the rotation movement of said shaft through corresponding ones of said slots and said gaps, each of said bodies varying in dielectric-affecting material in a direction circumferential along the respective paths of movement thereof to continuously change the total value of the dielectric across the said gaps, thereby giving rise to a continuously varying capacitance.

9. In an omnidirectional antenna system having a plurality of directional antennas coupled to a source of energy by a coaxial transmission line; means to continuously vary the phase of the energy fed to one or more of said directional antennas comprising a section of said coaxial transmission line having the inner conductor thereof with a gap therein, an inductive coaxial stub having the outer and inner conductors thereof coupled to the outer and inner conductors, respectively, of said line, the outer conductor of said line having a slot in alignment with said gap, a shaft disposed for rotation around an axis parallel to said coaxial line, means including a body carried on said shaft for movement during a rotation movement of said shaft through said slot and said gap, said body varying in dielectric-affecting material in a direc-

tion circumferential along the path of movement thereof to continuously change the total value of the dielectric across said gap, thereby giving rise to a continuously varying capacitance which in turn gives rise to a continuously varying phase shift in the energy flowing along said transmission line.

10. In an omnidirectional antenna system having four antenna arrays each having a directional radiation pattern of substantially 90°, wherein alternate antenna arrays are coupled together, the combination of patterns having narrow nulls between radiation lobes, means to continuously vary the phase of energy fed to one or more of said coupled antenna arrays comprising a coaxial transmission line having an outer conductor with a slot therein and an inner conductor with a gap therein in alignment with said slot, a coaxial stub having the inner and outer conductors thereof coupled to the inner and outer conductors, respectively, of said line, a shaft disposed for rotation about an axis parallel to said coaxial line, means including a body carried on said shaft for movement during a rotation movement of said shaft through said slot and said gap, said body varying in dielectric-affecting material in a direction circumferential along the path of movement thereof to continuously change the total value of the dielectric across said gap, thereby giving rise to a continuously varying capacitance and in turn a continuously varying phase shift in energy flowing along said transmission line resulting in a con-

tinuously varying pattern directivity so as to interchange said narrow nulls with said radiation lobes, whereby the resulting phase shift varies the pattern directivity to interchange said narrow nulls with said radiation lobes.

11. A phase shifter type device according to claim 1, wherein the said body comprises a disc of insulating material having conductive material carried by the peripheral portion thereof, said conductive material being of a radial dimension equal to a fraction of the diameter of the outer conductor of said coaxial line.

12. A device according to claim 8, wherein said plurality of bodies comprises a plurality of discs each composed of insulating material having conductive material carried respectively by the peripheral portion thereof, said conductive material being of a radial dimension equal to a fraction of the diameter of the outer conductor of said coaxial line.
